COIN-CONTROL MECHANISM FOR DISPENSING MACHINES

William Andrew Harris, Greenville, S. C.

Application March 23, 1939, Serial No. 263,759

8 Claims. (Cl. 194—48)

This invention relates to improvements in a coin controlled mechanism for dispensing machines described and claimed in my copending application Serial No. 229,184, filed September 9, 1938.

An object of the invention is the provision of a mechanism in which a coin is adapted to act upon a releasing mechanism so that one or a number of articles may be dispensed from the machine.

Another object of the invention is the provision of a coin-controlled mechanism for vending machines in which an operating device for causing the discharge of articles is locked against movement until an inserted coin releases instrumentalities which will throw out the locking device whereby one or a number of articles may be discharged depending upon the denomination of the coin inserted.

A further object of the invention is the provision of a coin-controlled mechanism for vending machines in which after a coin has been inserted in the usual coin slot and released to permit operation of the vending machine, a second coin may be inserted during the operation of said machine, but the second coin will be held in an inoperative position until a predesignated number of articles has been discharged by the action of the preceding coin, the coin-actuated elements being retained in an inoperating position until the predesignated number of articles have been discharged when the inactive coin will be released for again setting the vending machine elements so that another series of articles may be discharged.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a view in perspective of my dispensing machine shown in its housing.

Figure 2 is a vertical section taken along the line 2—2 of Figure 3.

Figure 3 is a vertical section taken along the line 3—3 of Figure 2.

Figure 4 is a longitudinal section taken along the line 4—4 of Figure 2.

Figure 5 is a fragmentary vertical section taken along the line 5—5 of Figure 4.

Figure 6 is an end view showing the coin controlled mechanism in an inoperative position.

Figure 7 is a fragmentary end view showing the speed preventing device in operative position.

Figure 8 is a fragmentary end view of the coin controlled mechanism in an operative position.

Figure 9 is a view in perspective of the rockable dispensing device.

Figure 10 is a view in perspective of that element of the dispensing device shown in Figure 9 for retaining articles in the machine when one article is being dispensed.

Figure 11 is a rear view in elevation of the dispensing device shown in Figure 9.

Figure 12 is an end view in elevation with the housing in section showing the coin control mechanism which is adapted to be operated by a cent.

Figure 13 is a fragmentary end view in elevation similar to that shown in Figure 8 disclosing the position of the locking means for the dispensing device in an operative position after the cent has been dropped into the coin slot for that purpose.

Figure 14 is a fragmentary view in elevation showing the locking means for the dispensing mechanism in an inoperative position when released by the mechanism actuated by a cent.

Figure 15 is a view in perspective of a pointer.

Figure 16 is a view in perspective of the operating lever for actuating the dispensing mechanism.

Figure 17 is a fragmentary view in perspective of the coin operating mechanism shown in Figure 6.

Referring more particularly to Figure 1, it will be seen that the housing 20 is provided for totally encasing the dispensing mechanism and this housing is provided with end walls 20 and 21, a removable front plate 22, a shelf 23, a supporting base member 24 and a front wall 25 extending downwardly from the outer edge of the shelf 23. The ends of the front wall 25 are connected in any approved manner to the front edges of extensions 26 of the end walls 20 and 21.

The front plate 22 is provided with a window 27 and a lock 28 for securing the front plate to the housing. This front plate is also provided with a coin slot 29 into which a nickel or a coin of a higher denomination is adapted to be deposited. At the opposite edge of the front plate there is also provided a coin slot 30 into which a cent is adapted to be deposited.

A bar 31 is secured to the lower end of the

front plate adjacent the shelf 23 and has a plurality of pockets 32 in which labels are placed with the names of the brands of the various articles which are adapted to be discharged from the housing.

The front wall 25 is provided with a slot 33 through which projects a slidably mounted operating handle 34 for positioning a selective operating means for the dispensing apparatus and for operating the dispensing apparatus when the handle is depressed.

A door 35 is pivotally mounted at 36 on the front wall below the handle 34 and is provided with a transparent panel 37 for inspecting the interior of a receptacle 38 into which the articles are dispensed when the machine is properly operated. A finger grip 39 is connected to the lower edge of the door 35 so that the door may be swung open whereby the operator of the dispensing machine may receive the articles discharged into the receptacle 38.

A chute 40 is located in the bottom of the housing and has flanges 41 which are secured to a pair of plates 40^a and 40^b which form part of the dispensing mechanism and furthermore these plates are independent of the walls of the housing. The lower end of the chute merges into the bottom 42 of the receptacle 38. A cover plate 43 is secured at 44 to the inner face of the front wall 25 and extends downwardly and rearwardly over the receptacle 38 in such a manner that it will be impossible for someone to insert a tool through the door 35 in an attempt to operate in an unauthorized manner the dispensing mechanism. The inner elevated end of the chute 40 terminates adjacent a rear wall 45 forming part of the housing 20.

This machine is particularly adapted for dispensing cigarettes successively, but it will be appreciated that this machine may be employed for dispensing any other type of article by merely changing the sizes of certain elements of the dispensing mechanism without departing from the principles of the invention.

Referring more particularly to Figure 2, it will be seen that the plates 40^a and 40^b are provided with flanges 50 which rest upon the bottom of the main housing. A table 51 connects the upper ends of the plates 40^a and 40^b and is formed integrally with said plates. A rear wall 52 (Figure 3) is provided with a flange 53 which is secured in any manner to the rear edge of the table 51. The wall 52 forms the back of a vertical compartment in which cartons of cigarettes are housed. This table has a depending flange 54 at its front edge as shown in Figures 2 and 3. A bar 55 is connected at its flanged ends 55^a to the plates 40^a and 40^b adjacent the rear edges of said plates (Fig. 4) while a bar 56 has its flanged ends 56^a connected to the same plates adjacent the depending flange 54 of the table 51. Both of these bars are located in parallel planes which are below the plane of the table 51.

The table is provided at spaced points with openings 57. A pair of spaced plates 58 and 59 are provided with flanged lower ends 60 which are secured to the top of the table upon opposite sides of each opening 57. It will be noted from Figure 5 that the upper ends of these plates are flared outwardly as shown at 61 to facilitate the insertion of a box or suitable container 62 which is filled with cigarettes and has a window at its front face at the lower end as shown at 63 whereby the cigarettes may be inspected from the exterior of the housing through the window 27. 75

These containers or magazines are described and claimed in my co-pending application Serial No. 229,186, filed September 9, 1938. These magazines may be inserted after the window 63 has been formed and after the lower ends have been opened to permit the discharge of cigarettes. Furthermore a magazine is located between each pair of plates 58 and 59 and each magazine may contain a different brand of cigarettes.

10 A U-shaped member more particularly illustrated in Figures 5, 9 and 11 and generally designated by the numeral 64 is provided with a pair of depending legs 65 and 66 and a bridging member 67 which normally is disposed below an opening 57 in the table 51 for retaining the cigarettes between the plates 58 and 59. Each pair of legs of the U-shaped members is rotatably mounted upon a shaft 68 which has bearings in the bars 55 and 56. Cotter pins 69 are carried by the ends of each of the shafts for maintaining the shafts in position.

The bridging member 67 of each U-shaped member is maintained in position beneath an opening 57 by a coil spring 70 which has one arm 71 engaging one edge of the leg 66 of the U-shaped member as shown at 72, while the other arm 73 of the spring has its end engaged over the upper edge of the bar 55 as shown at 74 in Figures 5 and 11. The coil spring 70 is mounted upon the shaft 68.

A finger 75 is secured to the lower end of the leg 65 and is provided with an opening 76 which receives the shaft 68.

A plate 77 is provided with bearings 78 which are received by the shaft 68 inwardly of the legs 65 and 66 of each U-shaped member and is mounted for a slight rocking movement on the shaft which is independent of the rocking movement of the U-shaped member 64. The upper edge of the plate is provided with fingers 79 which are received by notches 80 formed in the bridging member 67 of the U-shaped member 64. The outer free ends 81^a of each of these fingers are provided with an angularly formed keeper 81 which is adapted to be moved through vertically disposed slots 82 (Fig. 3) formed in each of the plates 58 so that the keeper 81 may engage beneath the next of the lowermost cigarette 83 which is housed between the plates 58 and 59 for maintaining a column of cigarettes against discharge when the lowermost cigarette is being dispensed and when the bridging member 67 is moved away from its respective opening 57 as will be presently explained.

55 A plate 84 has its upper end 85 bent at an angle and secured to the upper end of the plate 77 so that the lower portion of the plate will extend outwardly at an angle from the plate 77. The lower rear end of the plate 84 is provided with a curved article guiding member 86. The forward lower end of the plate 77 is provided with an article guiding member 87 which is curved in an opposite direction to the member 86.

It will be seen from Figure 5 that the article guiding member 86 of one dispensing unit crosses the curved plane passing through the shorter guiding member 87 of the next adjacent unit. When a cigarette is released through any one of the openings 57 the front end will move down and fall off of the forward finger 87 while the rear end of the cigarette is still engaged by the member 86. When this happens the cigarette will be turned from its transverse position to a position which is parallel to the front face of the housing

so that the cigarettes will roll into the receptacle 38 and be parallel to the door 35.

A spring member having a coil portion 90 (Fig. 9) received by the shaft 68 has an arm 91 extending upwardly therefrom and engaging over the top edge of the plate 77. The other arm 92 of the spring member engages over the top edge of the bar 55. Thus, it will be seen that the arm 91 will tend to press the plate 77 towards the U-shaped member 64 whereby the fingers 79 will be normally seated within the notches 80 of the bridging member 67 as shown in Figure 9. The fingers 79, however, are limited in their inward movement over the openings 57 and the table 51 by the outer extreme free end 81^a engaging the upper edges 83 of the plates 58 at the upper ends of the cutout portions or openings 82 in the plates 58. When the U-shaped member 64 is rocked to the right as shown in Figure 5, the plates 77 and 84 will likewise move with the U-shaped member because of the action of the spring 90 and after the member 81 has engaged the edge 93 on the plate 58 the plates 77 and 84 will be held against further movement and the member 81 will be engaged beneath the cigarette 83. When the U-shaped member is released the larger spring 70 will return the U-shaped member to its position beneath its respective opening 57 to force the plate 77 and the keepers attached to said plate and likewise the plate 84 to their normal inoperative positions against the action of the spring 90. The last-mentioned spring merely tends to force the spring 77 towards the U-shaped member 64.

A rock shaft 95 (Fig. 3) is mounted in bearings in the plates 40^a and 40^b and extends in parallel relation with the front wall 25 of the housing. A lever 96 shown more particularly in Figure 16 has a bearing 97 which is received by the shaft 95 and this lever is not only rockably mounted on the shaft but is also slidably mounted thereon. The handle 34 is integrally formed with the lever 96 and as has been explained it extends through an elongated slot 33 in the front wall of the housing. The lever has a depending flange 98 in which is formed a socket 99 to receive a rod 100 (Figs. 3 and 4). The ends of the rod 100 are connected by legs 101 to the ends of the shaft 95 so that when the rod 100 is elevated by the raising of the lever 96 when the handle 34 is depressed the shaft 95 will be rocked. The extreme end of the flange 98 has a toe 102 which is adapted to move through one of a plurality of slots 103 (Fig. 2) formed in the bar 56 and cut through the lower end of said bar. Each slot is located adjacent one of the shafts 68 and the toe 102 moves through said slots and it will engage the finger 75 rigidly connected with a respective U-shaped member 64 for raising the member 75 and thereby oscillating the U-shaped member as shown in Figure 5.

A pointer 104 (Fig. 15) is vertically disposed from the free end of a plate 105 which has bearings 106 loosely received by the shaft 95. The inner free end 107 of the plate 105 rests upon the upper edge of the bar 56 as shown in Fig. 3. The bearings 106 (Fig. 17) engage the opposite sides of the bearing 97 of the lever 96 so that when the lever is moved longitudinally of the shaft 95 the pointer 104 will likewise be moved but will remain stationary when the lever is rocked since the lever 96 is spaced a sufficient distance downwardly from the plate 105 which is slightly inclined upwardly from a horizontal

plane passing through the horizontal axis of the shaft 95 (Fig. 3).

It will be seen by this arrangement that when it is desired to dispense from the machine a particular brand of cigarettes as indicated by the pointer 32 in the main housing the handle 34 is moved along the slot 33 until the pointer 104 reaches the point directly at the rear of one of the labels 32 for the selected brand. The handle 34 is then depressed after a coin has been deposited in one of the coin slots 29 or 30 and the required number of cigarettes will be discharged into the receptacle 38 in accordance with the value of the coin deposited and in accordance with the number of oscillations of said lever as will be presently described.

If, on the other hand, the operator of the machine desires to obtain one or more cigarettes of one brand and the remainder of the number of cigarettes to which he is entitled of another brand, he may shift the lever to one of the brands desired and shift the pointer in alignment with one of the brands indicated by the tag 32 and operate the handle several times and then he may shift the pointer to the other brand and then operate the lever the required number of times. In this way the operator may obtain five cigarettes each of a different brand, or he may obtain five cigarettes of one brand, or he can divide them accordingly as he sees fit by the shifting of the lever longitudinally of the slot 33 to the proper positions.

At each time the lever 34 is oscillated the member 102 engages the finger 75, raising said finger and oscillating the U-shaped member 67 to the right.

The usual fraud detecting mechanisms are employed in association with the coin chutes and since these fraud detecting mechanisms form no part of the present invention they will not be described, although they are illustrated as part of the complete machine.

An angularly shaped apron 110 (Fig. 3) is secured to the inner faces of the plates 40^a and 40^b and extends beneath the longitudinal travel of the lever 96.

A coin control mechanism is set in operation by depositing a nickel in the slot 29 which coin 111 finds its way into a terminal chute 112 (Figs. 6 and 8) and is adapted to release a locking mechanism which retains normally the lever 34 against operation.

A lever 113 is pivotally mounted intermediate its ends upon a pin 114 carried by the plate 40^a. At one side of the pivot point 114 of the lever is provided an adjustably mounted weight 115 while the opposite free end 116 of the lever is adapted to move within the chute 112 and is adapted to be engaged by the coin 111 when the coin reaches the lower portion of said chute. A bracket 117 is secured to the lever 113 and has its free end 118 perforated to receive the pin 114. A second bracket 119 is secured at 120 to the plate 40^a and has its free end pressing against the end of the pin 114 and in close association with the free end 118 of the bracket 117 for maintaining the lever in position on the pin.

A combination means for retaining a lever 113 in its lowermost position and also for retaining the prematurely inserted coin 121 in an elevated position is represented by the lever 122 which has ears 123 pivotally mounted on a pin 124 secured to the plate 40^a. A bracket 125 secured at 126 to the plate 40^a has its free end engaging the outer end of the pin and likewise the outer

ear 123 for maintaining the lever 122 in position on the pin. A weight 127 projects outwardly from the lever 122 and is received between the plate 40^a and the bracket 125.

A lip 128 extends outwardly from the extreme upper end of the lever 122 and projects into the coin chute 112 when the lever 113 is locked in its lowermost position for obstructing the travel of a prematurely inserted coin 121 and retains said coin in an elevated position away from the free end of the lever 116 until the coin 111 is discharged and after the lever 122 is rocked to an inoperative position whence the coin 121 will fall and again operate said lever.

A pin 129 is connected to the lever 113 adjacent the lower end of the lever 122 so that it will be engaged by a tooth 130 formed on the lower end of the lever 122. This lever also at its lower end and below the tooth 130 is provided with a finger 131 for a purpose which will be presently described. The shaft 95 projects beyond the outer face of the plate 40^a and a lever 133 at its upper end is rigidly secured to said shaft so that as the shaft is rocked the lever 133 will likewise be rocked in a direction indicated by the arrow in Figure 8.

An angularly bent pawl 134 is pivotally connected at 135 with the lower end of the lever 133 and at this portion the pawl is provided with a weight 136. The free end 137 of the pawl is adapted to engage teeth 138 formed on the periphery of a wheel 139 which is rotatably mounted on a pin 140 secured to the plate 40^a. The free end of the pawl is supported by a hanger 137^a which depends from the lever 113.

A spring 139^a has one end connected to a pin 140^a carried by the lever 113 adjacent the weight 115. The free end 141 of the spring presses upon the top of the pawl 134 and a pin 142 carried by the lever 113 is engaged by the spring 139^a so that the free end 141 of the spring will exert pressure on the pawl and maintain it in its lowest position at the bottom of the hanger 137^a.

A strip of metal 143 is secured to the outer face of the lever 133 at 144. One end 145 of this strip is bent outwardly and forms a pocket with a raised portion 146 of the lever 133. The opposite end 147 of the strip is also bent outwardly and engages the pivoted end of the pawl 134. A pocket likewise is formed between the end 147 of the strip and the lever for a purpose which will be presently explained.

A locking device is shown at 150 (Figs. 6 and 8) and is pivoted at 151 on the plate 40^a. This locking device has a finger 152 received by the pocket located beneath the end 145 of the strip 143 and this finger is adapted to engage a lug 153 formed on the lever 133. A pin 154 projects from the member 150 and is engaged by the weighted end of the lever 113 so that when the end 116 of said lever is lowered the member 150 will be rocked and the finger 152 will be moved out of engagement with the lug 153. The member 150 as shown in Figure 17 is provided with a weight so that said member will tilt towards the weighted end of the lever 113 and maintain the pin 154 in engagement with said end of the lever.

The member 150 is also provided with a pin 155 adapted to be engaged by an arm 157 depending from a rod 156 which is supported in bearings in the plates 40^a and 40^b and this rod extends longitudinally of the housing where it projects beyond the outer face of the plate 40^b (Fig. 12) where a depending arm 158 extends

outwardly therefrom. The free end of the arm 158 is provided with a finger 159 for a purpose which will presently be explained.

A bar 160 is secured to the toothed wheel 139 with its opposite ends 161 and 162 extending beyond the teeth 138 of the wheel 139. The end 162 when moved through a predetermined arc by the rotation of the wheel 139 and the bar 160 and is located just to the left of the finger 131 (Fig. 8) is adapted to strike said finger when the wheel is further rotated to rock the lever 122 whereby the tooth 130 will be moved away from the pin 129 on the lever 113 and thus release the lever 113 to the action of the weight 150 whereby the free end 116 of the lever 113 will rise. The bar is provided with a laterally projecting pin 163 adjacent the end 161, while a pin 164 projects laterally from the bar and from the same face adjacent the end 162. A curved spring 165 is secured to the lever 113 and this spring is adapted to engage either one of the pins 163 or 164 when one of the ends 161 or 162 of the bar 160 is adapted to come into contact with the angularly formed free end 166 of a spring 167 secured at 168 to a bracket 169. A screw 170 connects a bracket 171 and likewise the bracket 169 to the plate 40^a. The free end of the bracket 171 engages the outer face of the bar 160 and likewise the pin 140 upon which the wheel 139 is rotatably mounted.

The operation of the coin control mechanism illustrated in Figures 6, 8, 13 and 17 is as follows: A nickel is deposited in the coin slot 29 and this coin will fall by gravity until it reaches the terminal chute 112, whence it will pass through the chute and engage the free end 116 of the lever 113 as shown in Figure 6 where the parts are disclosed in an inoperative position and where the finger 152 of the locking element 150 is in engagement with the lug 153 on the lever 133. When the lever 113 is depressed the weighted end of said lever will raise the pin 154 and thereby tilt the member 150 on its pivot 151 whereby the finger 152 will be released from the lever 133. The lever 133 is now free to be oscillated.

The handle 34 may then be shifted by the operator until the pointer 104 is directly opposite the brand desired. The handle 34 may then be depressed whereby, as has been previously explained, the U-shaped member 64 will be rocked away from an associated opening 57 in the table 50 while the member 81 will engage beneath the next to the lowermost cigarette to retain the column in position while the lowermost cigarette is being released by the movement of the U-shaped member 64.

Each time the lever 133 is moved by the rock shaft 95 in the direction indicated by the arrow in Figure 8, the free end 137 of the pawl 134 will engage a tooth 138 of the wheel 139 and rotate the wheel step-by-step while the spring 139^a presses upon the pawl to maintain said pawl in its lowest position in the hanger 137^a.

It must be borne in mind at this time that since the lever 113 has been lowered to the position shown in Figure 8 by the coin 111 the lever 122 which is in engagement with the pin 129 will also be tilted to the position shown in Figure 8 because the pin 129 will slip below the tooth 130 on the lever 122 and retain the lever in locked position and likewise the lever 113 so that the member 128 will be projected into the terminal chute 112 and the finger 131 will be moved to a position where it crosses the path of the moving end 162 of the revolving bar 160.

When the end 162 of the bar 160 approaches

the free end of the spring 165 the pin 164 will be engaged by the free end of the spring and this spring will exert pressure not only on the pin but also on the bar. At about the time that the spring 165 engages the pin 164 the free end 161 of the bar will engage the bent end 166 of the spring 167 and will tend to depress the spring so that the spring will exert pressure on the end 161 of the bar. When this end 161 of the bar passes over the raised portion 166 of the spring 167 said free end will slide rapidly beyond the raised portion and the combined action of the springs 165 and 167 will kick the bar rapidly from its vertical position so that the end 162 of the bar will be thrown against the finger 131 on the lever 122 and thereby kick this lever from its position as shown in Figure 8.

The release of the lever 122 from the pin 129 will likewise release the lever 113 so that the free end 116 of said lever will rise while the weighted end 115 will be lowered and the weighted locking member 150 will move in the direction indicated by the arrow in Figure 8 with the pin 154 following the lowered weighted end of the lever 113. The finger 152 of the member 150 will be raised and it will engage the lug 153 on the lever 133 and thus lock this lever against further operation.

As soon as the coin 111 falls on the free end 116 of the lever 113 it will be discharged into a receptacle 171 (Fig. 6). If a second nickel had been placed in the coin slot 29 before the lever 133 had been operated five times this second coin 121 will be held in an elevated position by the finger 128 on the lever 122 since it has been projected into the terminal chute 112 as shown in Figure 8 and will be maintained in this position as long as the lever 113 is held in its lowermost position by the lever 122 and the pin 129.

After the coin 111 has moved the lever 113 to its operative position (Fig. 8) and the lever 133 has been operated five times the lever 113 will then be released by the oscillation of the lever 122. The oscillation of the lever 122 removes the finger 128 from the chute 112 whereby the coin 121 will fall immediately and again contact the free end 116 of the lever 113 and move said lever to its locked position since the tooth 130 on the lever 122 will again engage the pin 129 and lock the lever 113 in its lowermost position so that the rotatable member 139 can be revolved through 180° by the oscillation of the lever 133 five more times for dispensing five more articles.

If the previous operator had failed to obtain less than five cigarettes to which he was entitled when he deposited the coin 111, the second operator will not only receive the remaining number of cigarettes which the prior operator had failed to obtain, but he will also receive the five cigarettes to which he was entitled by the deposit of said coin 121. Thus, it will be seen that the machine will always dispense at some time or the other all of the cigarettes or articles for the value of the coins deposited.

A centrifugally operated member 175 is pivotally mounted at 176 on the lever 133 in the pocket between the end 147 of the strip of metal 143 and the outer face of the lever 133. A spring has its intermediate coiled portion 177 mounted on the pin 176. One arm 178 of the spring extends outwardly from the pocket and engages a pin 179 on the member 175. The other arm 180 is engaged around the portion 147 of the strip of metal 143 so that the arm 178 will tend

to force the pin 179 and the member 175 upwardly towards a catch 181. This catch extends outwardly from a base member 182 which is secured to the plate 40^a. The member 175 is provided with a notched finger 183 which is adapted to engage the catch 181 when the lever 133 is operated too rapidly and when the operator attempts to force more cigarettes or articles from the machine than the amount of money deposited. A rapid oscillation of the lever 133 will cause the member 175 to swing upwardly whereby the finger 183 will engage the catch 181 and prevent further movement of the lever 133.

On the plate 40^b (Fig. 12) is mounted a mechanism for dispensing one cigarette at a time and this mechanism is controlled by depositing a cent in the coin slot 30. While certain details of the fraud detecting device are shown in Figure 12, these parts will not be described since any well known form of fraud detecting construction may be employed for the purpose.

A terminal coin chute 190 receives the cent 191 and this cent rolls downwardly and is adapted to engage the free end 192 of a lever 193 which is pivoted at 194 on the plate 40^b. This lever is provided with a weight 195 which tends to maintain the free end 192 of the lever 193 in an elevated position. A bracket 196 is secured at 197 to the plate 40^b and has its free end engaging the outer face of the lever 193 where said lever is pivoted on the pin 194. The weight 195 is adjustably positioned on the outer end of the lever 193 by means of a slot 198 and screws 199.

35 A pawl 200 is pivotally mounted on a pin 201 which is secured to the plate 40^b. A bracket 202 is secured at 203 to the plate 40^b and has its free end 204 engaging the outer face of the pawl 200 and the outer end of the pin 201 for maintaining the pawl in position on said pin.

30 The pawl 200 is provided with a cam portion 205 which is adapted to be engaged by a pin 206 secured to the outer face of the lever 193. This pin is adapted to be received in notches formed by shoulders 207 and 208. A pin 209 secured to the plate 40^b is adapted to engage the straight edge of the pawl 200 for limiting the rearward movement of the pawl so that the shoulders on the pawl will be in position to be engaged by the pin 206 on the lever 193.

The lever 193 has a finger 210 projecting from the weighted end 195 and this finger is in a position to engage the projection 159 on the arm 158 of the rockable rod 156.

55 A lever 211 is rigidly secured at its upper end to the shaft 95 so that when said shaft is rocked in the proper direction the free end of the lever will move in the direction indicated by the arrow (Figure 12). The free end of the lever 211 is connected with a spring 212 and this spring is also connected to a pin 213 on the plate 40^b. A second spring 214 has one end connected to the inturned end 215 on the lever 211 while the other end of the spring is connected at 216 with a lever 217 pivoted on a pin 218 carried by the plate 40^b.

A bracket 219 is secured at 220 to the plate 40^b which engages the outer face of the lever 217 and also the outer end of the pin 218 for maintaining the lever in position against the plate 40^b. A bracket 221 connected at 222 to one end of the lever 217 engages the free end of the pin 218 to which the lower end of the spring 214 is connected.

The free end 223 of the lever 217 engages a pin 224 secured to an operating arm 225 which rocks

a shaft 226 of a counting mechanism embodied in a housing 227 which is secured to the inner face of the front wall 25 of the housing. The front wall is provided with an opening 228 (Fig. 1) through which the numerals appear of the counting mechanism as the same is operated. This counting mechanism, however, forms no part of the present invention but is operated each time that the shaft 95 is rocked regardless of whether a cent has been placed in the slot 30 or a nickel has been placed in the slot 29 on the front of the main housing.

The operation of the cent controlled mechanism is as follows: When the cent 191 has been deposited in the slot 30 of the housing it will reach the terminal chute 199 and will fall down upon the free end 192 of the lever 193 and, therefore, lower it to the dotted line position shown in Fig. 12 and the pin 208 will engage below the shoulder 207 and lock the lever 193 in lowered position. The parts of the mechanism shown in Fig. 12 are in an inoperative position. When the free end 192 of the lever 193 is lowered the weighted end 195 will be raised and the finger 210 will raise the projection 159 on the arm 158 of the operating rod 156, and therefore, rock this rod so that the arm 157 will be rocked in the direction indicated by the arrow in Figure 13 to the dotted line position or in the full line position shown in Figure 14. When the arm 157 is moved in the direction indicated by the arrow it will engage the pin 155 on the locking member 150 and oscillate said member so that the finger 152 on the member 150 will be released from its engagement with the lug 153 on the lever 133. As has been previously explained when this occurs the lever 133 may then be rocked by depressing the handle 34.

As the handle 34 is depressed the shaft 95 will be rocked (Fig. 12) and the lever 211 will be elevated whereby the in turned end 215 will engage the cam portion 205 of the pawl 200 and move the pawl in the direction indicated by the arrow. When this happens the shoulder 207 on the pawl will be released from the pin 206 on the lever 193. Therefore, the free end of the lever 193 will rise while the weight 195 on the lever will be lowered. The finger 210 on the outer end of the lever will move away from the projection 159 and thus the rod 156 will be rocked to its inoperative position by the weight of the projection 159 and arm 157 since the projection and arm will fall by gravity when released. At this time the arm 157 assumes its vertical position as shown in Figure 13. The locking member 150 will oscillate on its pivot by gravity in the opposite direction indicated by the arrow (Fig. 8) so that the finger 152 of the member 150 will engage the lug 153 on the lever 133 and further operation of the lever will be prevented and no more articles can be dispensed from the machine.

It will be appreciated that when a cent has been placed in the machine and the lever 193 has been lowered to an operative position for releasing the locking member 150 and when the coin control mechanism on the nickel side has not been operated a sufficient number of times by a previous operator to release all of the cigarettes to which said operator of the machine was entitled then the party who has placed the cent in the machine will be able to operate the handle a number of times to release all of the cigarettes which had not been previously discharged. If the prior operator had left three undischarged

cigarettes in the machine the party who placed a cent in the machine will obtain only the three cigarettes and not one additional for the cent that he had placed therein. In other words six cigarettes cannot be obtained by placing a nickel and a cent in the respective slots simultaneously in the machine.

I claim:

1. A coin-controlled mechanism for vending machines provided with an operating element to release articles comprising a frame, a lever pivoted on the frame, means tending to elevate the lever, a chute directing a coin onto the free end of the lever for causing lowering of said free end, means for retaining the lever in lowered position, means connected with and actuated by the retaining means for holding a prematurely-inserted coin in an elevated and inoperative position in the chute, means normally locking the operating element of the vending machine against actuation, means operated by the lever when lowered for moving the locking means to an inoperative position, a rotatable means revolved by the operating element, a bar secured intermediate its ends to the rotatable means and revolved therewith, one end of the bar adapted to act on the retaining means and move the same to an inoperative position after said bar has been revolved through a predetermined angle, and a spring acting on the opposite end of the bar for causing said bar to be rotated rapidly when the first mentioned end of the bar engages the retaining means for causing quick release of the retaining means and the coin holding means whereby the lever and prematurely-inserted coin will be released.

2. A coin-controlled mechanism for vending machines provided with an operating element to release articles comprising a frame, a lever pivoted on the frame, a chute directing a coin onto the free end of the lever for causing lowering of said free end, means for retaining the lever in lowered position, means tending to raise the free end of the lever against the retaining means, a second lever actuated by the operating element of the vending machine and provided with a lug, a gravity-actuated pawl engageable with the lug and preventing rocking of the second lever, a pin projecting from the first lever and engaging the pawl so that when said lever is lowered the pin will rock the pawl to an inoperative position and free the second lever for operation, and means actuated by the second lever when rocked for releasing the retaining means.

3. A coin-controlled mechanism for vending machines provided with an operating element to release articles comprising a frame, a lever pivoted on the frame, chute directing a coin onto the free end of the lever for causing lowering of said free end, means for retaining the lever in lowered position, means connected with the retaining means and operated thereby for holding a prematurely-inserted coin in an elevated and inoperative position, a second lever actuated by the operating element of the vending machine and provided with a pocket and a lug in said pocket, a gravity-actuated pawl projecting into the pocket and engageable with the lug and preventing rocking of the second lever, means operated by the first lever when lowered for withdrawing the pawl from the lug, and means actuated by the second lever when rocked for releasing the retaining means and likewise the holding means for the prematurely-inserted coin.

4. A coin-controlled mechanism for vending machines provided with an operating element to release articles comprising a frame, a lever pivoted on the frame, a chute directing a coin onto the free end of the lever for causing lowering of said free end, means for retaining the free end of the lever in lowered position, means tending to raise the free end of the lever, a second lever actuated by the operating element of the vending machine and provided with a lug, a pawl pivotally mounted on the frame adjacent the levers and engageable with the lug to prevent actuation of the second lever, means operated by the first lever when lowered and engageable with the pawl for causing release of the pawl from the lug, and means actuated by the second lever for releasing the retaining means from the first lever.

5. A coin-controlled mechanism for vending machines provided with an operating element to release articles comprising a frame, a lever pivoted on the frame, a chute directing a coin onto the free end of the lever for causing lowering of said free end, means for retaining the lever in lowered position, means tending to raise the free end of the lever, a second lever actuated by the operating element of the vending machine, a pawl pivotally mounted on the frame adjacent the levers, a lug on the second lever engaged by the pawl and preventing operation of said lever, means on the pawl and acted on by the first lever for moving the pawl out of engagement with the lug when the first lever is lowered, and means operated by the second lever causing release of the retaining means.

6. A coin-controlled mechanism for vending machines provided with an operating element to dispense articles comprising a frame, a lever pivoted on the frame, means directing a coin onto the free end of the lever for causing lowering of said free end, means for retaining the lever in lowered position, a second lever having a pivoted mounting on the frame actuated by the operating element of the vending machine and provided with a lug, the pivotal mountings for the levers being adjacent each other, a pawl pivotally mounted adjacent the pivotal mountings of the levers and engageable with the lug to prevent actuation of the second lever, means operated by the lever when lowered for causing release of the pawl from the lug, a bar rotatably mounted intermediate the ends thereof on the frame, means actuated by the second lever for causing rotation of one end of the bar step-by-step towards the releasing means, and through a curved path, said releasing means being disposed across

the curved path and adapted to be engaged and moved by said free end of the bar to an inoperative position.

7. A coin-controlled mechanism for vending machines provided with an operating element to dispense articles comprising a frame, a lever pivoted on the frame, means directing a coin onto the free end of the lever for causing lowering of said free end, means for retaining the lever in lowered position, a second lever having a pivoted mounting on the frame actuated by the operating element of the vending machine and provided with a lug, the pivotal mountings for the levers being adjacent each other, a pawl pivotally mounted adjacent the pivotal mountings of the levers and engageable with the lug to prevent actuation of the second lever, means operated by the lever when lowered for causing release of the pawl from the lug, a bar rotatably mounted intermediate the ends thereof on the frame, means actuated by the second lever for causing rotation of one end of the bar step-by-step towards the releasing means, and a spring in the path of the moving ends of the bar adapted to engage the opposite end of the bar and force rapid rotation of the bar to rapidly strike the releasing means and move the same to an inoperative position.

8. A coin-controlled mechanism for vending machines providing with an operating element to release articles comprising means normally locking the operating element of the vending machine against actuation, a frame, a coin chute, a lever pivoted on the frame and having a free end projecting into the chute, said chute adapted to direct a coin onto the free end of the lever for lowering the same, said lever having means engageable with the locking means when the free end of the lever is lowered for moving said locking means to an inoperative position, means retaining the lever in lowered position, means causing the free end of the lever to be returned to a raised and inoperative position, means carried by the retaining means and projecting into the chute for holding a second coin prematurely inserted into the chute in an inoperative position until the lever has been released, and means actuated by the operating element for moving the retaining means to an inoperative position to release the lever and second coin retaining means so that the lever will again be lowered when the second coin is discharged upon the lever and release locking means.

WILLIAM ANDREW HARRIS.
